United States Patent Office

Des. 207,975
Patented June 20, 1967

207,975

ORGAN CABINET

Le Roy J. Ryan, Jr., 5300 W. Hutchinson,
Chicago, Ill. 60641

Filed May 3, 1966, Ser. No. 2,144

Term of patent 14 years

(Cl. D56—2)

FIG.1

FIG.2

FIG. 3

FIG. 4

FIG. 1 is a front perspective view of an organ cabinet embodying the new design;

FIG. 2 is a rear perspective view of the organ cabinet shown in FIG. 1;

FIG. 3 is a front elevational view of the organ cabinet shown in FIG. 1; and

FIG. 4 is a left end elevational view of the organ cabinet shown in FIG. 3, the opposite end being substantially a mirror image thereof.

The dominant features of the organ cabinet reside in the portions shown in full lines.

I claim:

The ornamental design of an organ cabinet, substantially as shown and described.
